FASTENING FOR PACKAGES

Michl Wollner and Franz Weber, Klenberg,
Czechoslovakia, assignors to the Firma Moldau-
mühl Brüder Perak, Papier und Pappfabri-
ken A. G., Klenberg, Bohemia, Czechoslovakia

Application March 8, 1935, Serial No. 10,113
In Czechoslovakia November 25, 1932

1 Claim. (Cl. 229—47)

The object of the present invention is to enable two or more members to be quickly and reliably connected with one another, as is required for example in the case of cardboard boxes, packing cases, and other packing means.

The invention is illustrated by way of example in the accompanying drawing, in which

Fig. 1 is a perspective view of the bent member,

Fig. 2 is a perspective view of part of one of the plates,

Figure 3 shows these two parts assembled,

Figure 4 shows in sectional elevation these two parts assembled with the outside plate, and

Figure 5 is a perspective view of a complete box fastened according to the invention.

A bent member *a*, as shown in Figure 1, is passed through a plate *b* provided with holes, as shown in Figure 2, and two lugs *c*, forming parts of the bent member *a*, are folded over as shown in Figure 3.

A plate *d* provided with a hole is now placed upon the projecting member *a*, in such a way that the two plates *b* and *d* lie one upon the other. Through the bent member *a*, where it projects above the plate *d*, is passed a tying member *e*, as shown in Figure 4.

It is obvious that the above described construction may be applied to many different forms of containers, as for example those with a double flap hinged closure or those of two parts telescoping one into the other.

In Figure 5 is shown a receptacle having closure flaps, which is equipped at two opposite ends

with bent members *a*, the tying means *e* being passed through both the members *a*.

The tying means *e* is now connected in any convenient manner, and the receptacle is in this way completely fastened.

The object of the bent member is to prevent displacement of the closure flaps and to render impossible the stripping off of the steel band.

What we claim is:—

Fastening means for boxes and like packages, comprising an inner flap formed with three holes in a line with one another, an outer flap formed with one hole registering with the middle hole in the inner flap, a stirrup member having its central portion and its two ends bent upwards, the central portion of the stirrup member extending in an outward direction through the middle hole in the inner flap and through the hole in the outer flap and projecting above the surface of the outer flap in the form of a loop, and a binding strip adapted to pass through the projecting loop of the stirrup member outside the flaps and right round the box or package the bent up ends of the stirrup extending through the other two holes in the inner flap and the end portions bent over the inner flap toward the strip whereby any outward strain on the strip tends to bind said bent-over end portion more tightly between the flaps and prevent pulling out the stirrup member.

MICHL WOLLNER. 30
FRANZ WEBER.
